Primary Examiner — Lilyana Bekic(74) *Attorney, Agent, or Firm* — Goodwin Procter LLP(57) **CLAIM**

The ornamental design for a pump device, as shown and described.

DESCRIPTION

FIG. 1 is a front perspective view of a pump device;
 FIG. 2 is a front of the pump device;
 FIG. 3 is a rear view of the pump device;
 FIG. 4 is a tight side view of the pump device;
 FIG. 5 is a left side view of the pump device;
 FIG. 6 is a top view of the pump device;
 FIG. 7 is a bottom view of the pump device; and,
 FIG. 8 is a rear perspective view of the pump device.
 The broken lines shown in the drawings depict portions of
 the pump device that form no part of the claimed design.
